UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, LONDON, ENGLAND.

BREECH-LOADING ORDNANCE.

Application filed August 25, 1926, Serial No. 181,491, and in Great Britain September 16, 1925.

This invention relates to breach loading ordnance of the semi-automatic type in which part of the breech actuating mechanism co-operates with a pawl on the cradle, 5 during the run-out movement of the gun, so as to open the breech and energize a spring which, when the gun is re-loaded, operates to close the breech. The said part of the breech actuating mechanism has usually been constituted by a cam mounted on the breech actuating crank shaft and formed with a toe which strikes the end of the pawl during the run-out movement, and it has been found in some instances that the force of the impact between the toe and the pawl is so great 10 as to throw the gun out of alignment to such an extent as to necessitate re-setting.

According to the present invention in order to obviate the above-mentioned disadvantage 20 the pawl is formed with a curved or inclined operating surface and the aforesaid cam is replaced by a crank having a lateral pin or projection which co-operates with the said operating surface during the run-out movement 25 of the gun so as to give a gradual angular movement of the crank and the actuating shaft on which it is mounted, instead of the sudden movement produced by the impact of the toe of the cam with the end of the pawl 30 as aforesaid. The pawl may be pivoted in a bracket which is attached to the cradle and has a surface upon which the lower part 35 of the pawl rests when in its operative position, the pawl being resiliently held in this position by a suitably arranged spring. The upper part of the pawl is formed with the aforesaid operating surface with which the pin or projection on the aforesaid crank co-operates, during the run-out movement 40 of the gun, to open the breech. When the gun occupies the normal run-out or firing position the said pin or projection, is situated in front of the pawl so that when the breech is closed the pin or projection can pass beneath the pawl at the next recoil movement 45 of the gun, the said pin or projection during this movement co-operating with a lower curved or inclined surface on the pawl to lift the latter against the resistance of its spring. 50 When the pin or projection has passed to the rear of the pawl the latter is returned by its spring to the operative position ready to operate the crank during the next run-out movement of the gun as described above.

55 The pawl can be moved to the inoperative

position when the gun is to be used as an ordinary quick-firing gun and for this purpose the said pawl may have a lateral projection disposed in a recess in a manually operated spring-controlled plunger arranged longitudinally in the aforesaid bracket, the said projection preferably serving to prevent rotation of the plunger. This plunger may be operated by a handle which is pivoted to the outer end of the plunger and has cam or eccentric surfaces bearing against the said bracket.

In order that the said invention may be clearly understood and readily carried into effect, the same will now be described more 70 fully with reference to the accompanying drawings, in which:—

Figure 1 is a local rear elevation shewing a constructional form of our improvements,

Figure 2 is a section taken approximately 75 on the line 2, 2 of Figure 1 and shewing the parts in different positions they occupy during the recoil movement of the gun,

Figure 3 is a view similar to Figure 2 but with the gun and gun cradle omitted, shew- 80 ing the crank in different positions it occupies during the run-out movement of the gun,

Figure 4 is a section taken approximately 85 on the line 4, 4 of Figure 1 shewing the pawl in the operative position for semi-automatic operation of the breech mechanism.

Figure 5 is a view similar to Figure 4 shew- 90 ing the pawl in the inoperative position which it is caused to occupy when the breech mechanism is to be opened by hand during "quick firing" operation, and

Figure 6 is a local section taken approxi- 95 mately on the line 6, 6 of Figure 4 and viewed from the left hand side of the latter figure.

A represents part of the breech end of the gun and B represents part of the gun cradle. C represents the aforesaid crank on the breech actuating crank shaft, this crank being provided with the aforesaid lateral pin or projection C' which is suitably shaped but which might be replaced by a roller. D represents the aforesaid pawl having a pivot D¹ disposed in a hole E in a bracket E' attached to the cradle B, the said pivot being retained in position by means of a pin e carried by the bracket E'; this pin passes through a hole in the pivot which hole has flared ends as shewn in Figure 4 to permit the required angular movements of the pawl to occur. The said pawl has a curved upper surface d disposed 100

in the path of the aforesaid lateral pin or projection C¹ during the run-out movements of the gun and has also a lower curved surface d² disposed in the path of the said lateral pin or projection during the recoil movements of the gun. At a position outside the path of the said lateral pin or projection, the lower part of the pawl D is shaped as shewn more particularly in Figures 2 and 3 and bears against a correspondingly shaped portion of the bracket E¹ where it is normally retained by a spring plunger e¹ carried by the said bracket. This bracket is, of course, so formed that the lateral pin or projection C¹ clears it during the recoil and run-out movements of the gun. The said bracket is also formed with a recess e² as shewn more particularly in Figure 2 so as to permit the pawl D to be raised into the position shewn by chain lines in that figure as will be herein-after described. In the run-out position of the gun with the breech mechanism closed, the crank C occupies the position shewn at the left-hand side of Figure 2 with the lateral pin or projection C¹ situated in front of the pawl D. During the recoil of the gun the pin or projection C¹ bears against the lower surface d¹ of the pawl and raises the latter into the position shewn by chain lines in Figure 2, the said pin or projection then clearing the pawl D which is returned by the spring plunger e¹ to the position shewn by full lines in Figure 2. At the end of the recoil movement of the gun the crank and its pin or projection occupy the position shewn at the right-hand side of Figure 2. On the run-out movement of the gun the pin or projection C¹ co-operates with the upper surface d of the pawl as shewn in Figure 3 thereby angularly displacing the crank C in order to open the breech mechanism. The position of the crank C at the end of the run-out movement of the gun and with the breech mechanism open is shewn at the left-hand part of Figure 3 and as the breech mechanism closes the crank and its pin or projection return to the position shewn at the left-hand part of Figure 2.

D² represents the aforesaid lateral projection on the pawl D and F represents the manually operated and spring-controlled plunger by which the pawl can be moved into the inoperative position shewn by Figure 5 when the gun is to be used as an ordinary quick-firing gun, that is to say when the breech is to be opened by hand. This plunger is arranged longitudinally in the bracket E¹ and at its front portion is provided with a recess in which the lateral projection D² on the pawl engages, the said recess having a flat surface (see Figure 6) situated beneath the lateral projection D² so that the latter serves to prevent rotation of the plunger F. The spring F¹ of the said plunger is situated in an axial recess in the plunger with the front end of the spring bearing against the end of this recess.

The rear end of the spring abuts against a plug F² which is connected to the bracket E¹ by means of a pin f² which passes through a hole in the plug F², a hole in the bracket E¹ and a slot f in the plunger F so as to permit the plunger to move longitudinally with respect to the plug F². At its rear end the said plunger has pivoted thereto a handle F³ which is provided with cam or eccentric surfaces f³ bearing against the contiguous rear surface of the bracket E¹. When the said handle is pointing downwards as shewn in Figure 4 the spring F¹ holds the plunger F in the position shewn in that Figure such that the pawl D is free to occupy the operative position above described with reference to Figures 2 and 3, but when the handle is moved into the position shewn in Figure 5 the cam surfaces f³ retract the plunger F and the pawl D is thereby held in the inoperative position shewn in that figure such that it is out of the path of the lateral pin or projection C¹ and the crank C is therefore not operated during the run-out movement of the gun.

The herein described pawl and crank can be used with breech mechanism having either a horizontally sliding breech block or a vertically sliding breech block and in the latter case the balancing spring and the main closing spring described in the specification of our patent application filed concurrently herein-with can, with advantage, be employed.

What we claim and desire to secure by Letters Patent of the United States is:—

1. In breech-loading ordnance of the semi-automatic type, a cradle for the gun, breech-actuating mechanism therefor, a crank connected to said mechanism, and means on said cradle and on said crank for giving said crank an initially slow and gentle opening movement, a gradually increasing angular acceleration, and a final high rate of angular movement, as and for the purposes specified.

2. Breech loading ordnance of the semi-automatic type, comprising a cradle, a pawl thereon having two operating faces, a crank forming part of the breech mechanism and mounted on a breech actuating shaft, a spring for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said crank and its breech actuating shaft, thereby preventing the setting-up of unbalanced forces on said breech whereby the lay of the gun is not disturbed.

3. Breech loading ordnance of the semi-

- automatic type, comprising a cradle, a pawl thereon having two operating faces, a crank forming part of the breech mechanism and mounted on a breech actuating shaft, a 5 spring for closing the breech, a lateral projection on said crank cooperating with one of said pawl operating surfaces during the run out movement of the gun to energize said spring, said projection cooperating with the 10 other surfaces of said pawl during recoil to rock said pawl which returns into operative position before the run out commences, the operating faces on said pawl having such a shape in relation to the shape of the face of said crank as to give, during the run out, a gradual, accelerating angular movement to said 15 crank and its breech actuating shaft, and a manually operated and spring-controlled plunger arranged longitudinally in the supporting bracket of said pawl, said pawl having a lateral projection disposed in a recess 20 in said plunger. 65
- 15 6. In breech-loading ordnance as in claim 2, the combination with the elements claimed in claim 2 of a manually operated plunger arranged longitudinally in the bracket in 70 which the pivoted member is mounted, a spring controlling said plunger, a lateral projection on said member, said projection engaging in a recess in said plunger so as to prevent rotation thereof. 75
- 20 7. In breech-loading ordnance as in claim 2, the combination with the elements claimed in claim 2 of a manually operated plunger arranged longitudinally in the bracket in 75 which the pivoted member is mounted, a spring controlling said plunger, a lateral projection on said member, said projection engaging in a recess in said plunger so as to prevent rotation of the latter, a handle pivoted to the outer end of said plunger and 80 cam surfaces on said handle for bearing against said bracket so as to retract said plunger and lift said pivoted member when said handle is operated. 85
- 25 8. In breech loading ordnance of the semi-automatic type, the combination of a crank connected to the breech actuating mechanism, a lateral projection on said crank, and a member on the cradle having an operating surface giving a gradual angular movement to 90 said crank during the run-out movement of the gun, said member also having another surface with which said lateral projection co-operates during the recoil movement of the gun to lift said member, and a spring 95 for returning said member to its original position when the lateral projection has passed to the rear of said member. 100
- 30 5. Breech loading ordnance of the semi-automatic type, comprising a cradle, a pawl thereon having two operating faces, a crank forming part of the breech mechanism and mounted on a breech actuating shaft, a spring 105 for closing the breech, a lateral projection on said crank cooperating with one of said 110
- 35 4. Breech loading ordnance of the semi-automatic type, comprising a cradle, a pawl thereon having two operating faces, a crank forming part of the breech mechanism and mounted on a breech actuating shaft, a spring 115 for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said 120 crank and its breech actuating shaft, and a manually operated and spring-controlled plunger arranged longitudinally in the supporting bracket of said pawl, said pawl having a lateral projection disposed in a recess 125 in said plunger. 130
- 40 5. Breech loading ordnance of the semi-automatic type, comprising a cradle, a pawl thereon having two operating faces, a crank forming part of the breech mechanism and mounted on a breech actuating shaft, a spring for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said crank and its breech actuating shaft, and a manually operated and spring-controlled plunger arranged longitudinally in the supporting bracket of said pawl, said pawl having a lateral projection disposed in a recess in said plunger. 135
- 45 6. Breech loading ordnance of the semi-automatic type, comprising a cradle, a pawl thereon having two operating faces, a crank forming part of the breech mechanism and mounted on a breech actuating shaft, a spring for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said crank and its breech actuating shaft, and a manually operated and spring-controlled plunger arranged longitudinally in the supporting bracket of said pawl, said pawl having a lateral projection disposed in a recess in said plunger. 140
- 50 7. Breech loading ordnance of the semi-automatic type, comprising a cradle, a pawl thereon having two operating faces, a crank forming part of the breech mechanism and mounted on a breech actuating shaft, a spring for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said crank and its breech actuating shaft, and a manually operated and spring-controlled plunger arranged longitudinally in the supporting bracket of said pawl, said pawl having a lateral projection disposed in a recess in said plunger. 145
- 55 8. Breech loading ordnance of the semi-automatic type, comprising a cradle, a pawl thereon having two operating faces, a crank forming part of the breech mechanism and mounted on a breech actuating shaft, a spring for closing the breech, a lateral projection on said crank cooperating with one of said pawl operating surfaces during the run out movement of the gun to energize said spring, said projection cooperating with the other surfaces of said pawl during recoil to rock said pawl which returns into operative position before the run out commences, the operating faces on said pawl having such a shape in relation to the shape of the face of said crank as to give, during the run out, a gradual, accelerating angular movement to said crank and its breech actuating shaft, and a manually operated and spring-controlled plunger arranged longitudinally in the supporting bracket of said pawl, said pawl having a lateral projection disposed in a recess in said plunger. 150
